UNITED STATES PATENT OFFICE.

CHARLES S. HORTON, OF HUNTLEY, MONTANA.

MANIFOLD-HEATER.

1,340,770.

Specification of Letters Patent. Patented May 18, 1920.

Application filed November 11, 1919. Serial No. 337,158.

To all whom it may concern:

Be it known that I, CHARLES S. HORTON, a citizen of the United States, residing at Huntley, in the county of Yellowstone and 5 State of Montana, have invented new and useful Improvements in Manifold-Heaters, of which the following is a specification.

This invention relates to attachments for internal combustion engines of automobiles 10 and has for its object the provision of a device for heating the intake manifold of the engine whereby to facilitate starting even in very cold weather and whereby the engine may be run even though cold without 15 using an excessive amount of fuel.

An important object is the provision of a device of this character which is formed as a metal shield or shell disposed against and partially embracing the intake manifold, 20 this shell being provided with a hole for the passage of one of the stud bolts holding the arms which secure both the intake and exhaust manifolds upon a very popular type of engine, and the shell being furthermore 25 provided with an apertured ear for the passage of one of the bolts which connect the carbureter flange with the manifold, the shell having its extreme lower portion containing an asbestos wick or pad adapted to 30 be saturated with gasolene which when ignited will effectually heat the intake manifold.

An additional object is the provision of a device of this character which will be extremely simple and inexpensive in manufacture, which may be readily installed by even an unskilled person, which will be efficient and thorough in operation, durable in service, and a general improvement in the art.

With the above and other objects and advantages in view, the invention consists in the details of construction to be hereinafter more fully described and claimed, and illustrated in the accompanying drawings in 45 which—

Figure 1 is a side elevation showing my device in position,

Fig. 2 is a similar view showing my device in longitudinal section,

Fig. 3 is a cross sectional view on the line 3—3 of Fig. 1,

Fig. 4 is a cross sectional view on the line 4—4 of Fig. 1, and

Fig. 5 is a perspective view of my device 55 detached.

Referring more particularly to the draw-

ings, the letter A designates the engine of a very popular type of automobile, this engine being provided at one side with exhaust and intake manifolds B and C, respectively, and having a carbureter D connected with the intake manifold C by the usual flanges E through which pass bolts F. The letter G designates the stud bolts carrying the arms H which hold the manifolds in place. 60 65

In carrying out my invention I provide a shell or shield 10 which is formed from a single piece of sheet metal cut and bent as shown, to provide a body which is substantially U-shaped in cross section throughout 70 the major portion of its length, and including sides 11 and 12 connected by a wall 13. This shell or shield is adapted for disposition upon the intake manifold C in partially embracing relation thereto and the side 11 is 75 provided at its upper end with a hole 14 for the passage of one of the stud bolts G. When the device is in position the lower end thereof extends below the bend in the intake manifold, as clearly shown, and this lower end 80 of the shield or shell is formed as a pan 15 which contains a pad 16 of asbestos or the like retained in position as by means of a trapezoidal yoke 17 mounted within a bearing loop 17^a and urged into engagement with 85 the pad by a spring 17^b. When burnt out, the pad may be easily replaced, as will be obvious. Also formed at the lower portion of the shell is an ear 18 which is apertured for the passage of one of the bolts F. 90

With the device constructed and installed as shown and described, its use is as follows:

When it is desired to start the engine, the operator pours onto the pad 16 a small quantity, such as a tablespoonful or two, of gasolene which he subsequently ignites. The flame from the burning gasolene will rise within the shell 10 and will play upon the intake manifold C, thoroughly heating it so 95 that when the engine is cranked the mixture passing through the intake manifold will be properly heated so that ignition will readily occur in the engine cylinders. It will therefore be seen that the engine may 100 not only be easily started but may be started and run even in very cold weather without any necessity for opening the carbureter adjustment to give a richer mixture. 105

From the foregoing description and a 110 study of the drawings it will be apparent that I have thus provided a device for the

purpose specified which is not only extremely simple and inexpensive in manufacture and installation, but which will very efficiently perform the function for which it is intended.

While I have shown and described the preferred embodiment of my invention, it is of course to be understood that I reserve the right to make such changes in the form, 10 construction, and arrangement of parts as will not depart from the spirit of the invention or the scope of the subjoined claim.

Having thus described my invention, I claim:

- 15 An attachment for an internal combustion engine provided with intake and exhaust manifolds secured in place by arms carried

by studs, comprising a metallic shield disposed in partially embracing relation to the intake manifold and including side portions, 20 one side portion being provided with a hole for the passage of one of said studs, said shield extending below the intake manifold and having its lower portion formed as a reservoir, an ear formed at the lower portion of the shield and apertured for the passage of one of the bolts securing the intake manifold to the carburetor flange, and an absorbent pad within said reservoir portion adapted to be saturated with an inflammable 25 30 liquid.

In testimony whereof I affix my signature.

CHARLES S. HORTON.
